JOHN H. HOLLOWAY, OF LA FAYETTE, INDIANA

GRAPHOPHONE CLOCK

Application filed December 12, 1927. Serial No. 239,496.

This invention relates to an electrically actuated clock and particularly the electric motor thereof.

The chief object of the invention is to provide an electric motor suitable for adaptation or incorporation in a clock of conventional design for main spring replacement, which motor operates with very little current, in fact, such a small amount that the load does not register upon meters now in commercial use if the motor be the sole load connected to the line.

Another object of the invention is to produce a clock which is adapted to audibly indicate the time division such as the hours and half hours, and thru means which are capable of amplification if and when desired.

The chief feature of the invention consists in the accomplishment of the foregoing objects thru a clock construction including means for operating the same.

The chief feature of the motor consists in providing a rotatable disk positionable between electromagnetic poles in such a manner that the magnetic flux or lines of force therefrom pass thru the disk and induce a magnetic field producing torque and causing the disk to rotate, and in brief the device may be defined as a split phase induction disk type electric motor.

The full nature of the invention will be understood from the accompanying drawings and the following description and claims:

In the drawings Fig. 1 is a front elevational view of a clock of conventional design with the motor applied thereto. Fig. 2 is a side elevational view thereof. Fig. 3 is a plan view taken in the plane of the broken line 3—3 of Fig. 2 and in the direction of the arrows. Fig. 4 is a wiring diagram of connections. Fig. 5 is a side elevational view of a modified form of the invention showing the auditory time indicating attachment. Fig. 6 is a front elevation of the same. Fig. 7 is a side elevation of a modified form of auditory reproducer.

The clock mechanism illustrated herein consists of the usual framework comprising

the front plate 10 and rear plate 11 with the spacing connections 12. Shaft 13 mounts a pinion 14 meshing with gear 15 upon shaft 16, which also supports a pinion 17 meshing with gear 18 that is mounted upon the minute hand shaft 19, the minute hand 20 being mounted upon the extended end of said shaft.

The hour hand 21 is mounted upon a sleeve 22 which mounts a gear 23 meshing with a pinion 24 carried by shaft 25 supported in the bracket 26 (see Fig. 1). Shaft 25 carries gear 27 which meshes with gear 28 carried by the minute hand shaft, the gear reduction being such that the hour hand rotates one hour division for every revolution of the minute hand.

The control or escapement mechanism of the clock consists of a pinion 128 meshing with gear 18 upon the minute hand shaft 19, said pinion being mounted upon a shaft 29 which carries gear 30 meshing with the pinion 31 carried by the shaft 32. Upon the extended end of shaft 32 is a gear 33 and a bracket 34 supports the extended end of said shaft. Gear 33 meshes with pinion 35 on shaft 36 mounted in bracket 37 and said shaft supports the escapement wheel 38 associated with which is the escapement lever 39 cooperating with the balance wheel 40 on shaft 41, the lever 42 regulating the clock escapement movement. All of the foregoing is a rather sketchy description of enough of the essential parts of a standard clock mechanism to understand the same.

The motor for driving shaft 13 instead of a main spring mechanism, consists of a thin metallic disk 43 mounted upon the projecting end of shaft 13 at 44. The thin projecting disk 43 passes between a pair of magnets which are axially offset relative to each other. The relationship is such that the magnetic flux or lines of force which pass from one magnetic pole to the other pass thru the disk and by reason of the angular direction of the flux and the eddy currents induced in the disk, there is set up a magnetic field which produces torque and causes the disk to rotate. The displacement of the magnetic poles is such that the magnetic flux of one is acted upon by the magnetic flux produced by the eddy currents of the other and in the disk and

this produces torque which causes the disk to rotate.

The electromagnet poles are shown in multiple, that is, the U-shaped upper magnet 45 is positioned upon one side of the disk path and opposite therefrom is another U-shaped magnet 46, the pole faces 47 and 49 of the former being offset or displaced laterally the width of one pole face or thereabouts 10 from the pole faces 48 and 50 of the latter U-shaped magnet. Upon the arms of the U-shaped magnet 45 are a pair of coils 51 and upon the arms of the U-shaped magnet 46 are the coils 52. The disk 43 is included in both 15 electro-magnet circuits and completed the electromagnetic circuits. The coils 52 are connected in series by the jumper 53. One terminal of one of the coils 52 is connected by the line 54 to L-1 and the other terminal being connected to L-2 by line 55. Coils 51 are connected in multiple instead of in 20 series, the lines 56 from each being connected together and the lines 57 from each being connected together. The common lines 56 are 25 connected by line 58. Condenser 59 is connected by line 60 to the supply line L-1, while the supply main L-2 is connected to the common lines 57 by the line 61. The series connected coils 52 are highly inductive and, 30 therefore, the current lags behind the voltage. The other coils, which are connected in multiple, are not as highly inductive and by reason of the multiple connection and also the 35 interpositioning of a condenser, the current wave precedes the voltage wave and the result is a displacement of flux maximums from the normal condition of voltage relation, the series coil flux lagging and the multiple coil flux advancing. The constants of each 40 circuit can be arranged to secure any predetermined phase relationship. The result, therefore, is an induction type motor having a disk rotor and which is operable upon the split-phase, the principal operation being as 45 before described. As the flux passes thru the disk from one electromagnetic pole to the other of the same U-shaped magnet, it also sweeps along parallel to the disk and cutting the disk, thereby inducing eddy currents in 50 said disk.

Each electromagnet construction is similarly acting but acts at different times by reason of the split-phase relationship. Furthermore, the polarity of the opposed poles, 55 that is, those which are slightly offset, is such that the magnetic flux of one is influenced by the magnetic flux of the other produced by the eddy currents in the disc and there thereby results certain magnetic flux of the correct 60 polarity and occurring at the correct instant.

While in the present invention U-shaped magnets are illustrated, the simplest form of the invention includes but a single or bar magnet, the pole faces being offset substantially the width of a pole piece. The U-

shaped magnet arrangement merely multiplies the efficiency and secures greater torque for the same amount of current. The energy consumed by the device such as herein illustrated, is less than four watts per hour which as is well known, is less than the present household commercial meters are prepared to register. Of course, if a registrable load is included in the meter circuit, the clock motor load is added thereto and will be registered.

A base 62 is substantially angular and the arm 63 is secured at 64 to the front plate 10 of the clock. The base 62 supports a condenser 59 at as 65, one terminal being shown at 66. The U-shaped magnets 45 and 46 are comprised of laminations secured together and mounted in spaced relation upon the base 62 as at 67. Also supported thereby is a terminal block 68 supporting the terminals L-1 and L-2 and supported upon the U-shaped keeper 46 by the brackets 69.

In Figs. 5, 6 and 7 there is illustrated a modification of the clock mechanism. The same includes the main front plate 110, and the hour hand shaft 122 is extended from the plate and mounts a phonograph disk 150. A spiral spring 151 has one end connected to said disk at 152 and the inner end connected to the shaft as at 153. The disk 150 upon its front face has a groove 154 which includes vibration producing variations corresponding to vocal designation of the hour and half hour. Twenty-four pins or stops 155 project rearwardly from the plate and form twenty-four half hour divisions. Pivotaly supported in the bracket or ears 156 at 157 is a bellcrank 158 normally retained in position by a spring 159 secured to a member 160 carried by plate 110. The stop portion 161 of the bellcrank 158 limits clockwise movement (see Fig. 5) on pivot 157. In the rotation of hour hand shaft 122 the spring 151 is wound up until its tension is sufficient to overcome spring 159. When this occurs the disk 150 is rotated by spring 151 in opposition to the stop 158 which is tilted upon its pivot counterclockwise by spring 151 overcoming spring 159. After stop 155 has passed over stop 161, the bellcrank spring 159 immediately projects the bellcrank into the path of the next succeeding stop and since spring 151 has exhausted its pressure or power the next stop engages bellcrank 158 and remains in engagement until the movement of the hour hand 122 is sufficient to store enough energy in spring 151 to compress the same and again overcome the resistance of spring 159.

This substantially rapid step by step rotation of disk 150 is translated into a vocal record. A cone 165 supported by bracket 166 has its registering point 167 engage in the groove 154. If desired the disk 150 may have the groove 154 engaged by a needle 170 carried by an arm 171 forming a part of the

diaphragm 172, which diaphragm discharges thru a horn 173. If desired, the foregoing cone or diaphragm types of reproducing can be interchanged or substituted, or can be amplified by radio amplification, all of which is well known in the art.

The invention claimed is:

1. In a clock, a rotating shaft, a rotatable sound reproducing disc, a spring connected at one end to said shaft and at its other end to said disc, a stop, and a spring holding said stop in engagement with said disc, said stop spring overcome by tension of said first mentioned spring when the shaft has reached a predetermined position.
2. In a clock, the combination of a constantly rotating shaft, a sound reproducing disc rotatable therewith, a yielding connection therebetween, a plurality of stops upon said disk and equal to the number of predetermined intervals, a yielding stop arrangement successively engaging the several stops for preventing rotation of the disk by the shaft except at predetermined intervals, said intermittent rotation being in amount equal to that between adjacent pairs of stops.

In witness whereof, I have hereunto affixed my signature.

JOHN H. HOLLOWAY.
